UNITED STATES PATENT OFFICE.

HENRY H. MERCER, OF CLAREMONT, NEW HAMPSHIRE, ASSIGNOR TO SULLIVAN
MACHINERY COMPANY, A CORPORATION OF MASSACHUSETTS.

MOTOR.

Application filed February 25, 1919. Serial No. 279,151.

My invention relates to motors, and more especially to pressure fluid operated motors.

It has for its object to provide an improved motor, and more especially one having increased efficiency and power. Another object of the present invention is to provide an improved motor which will occupy a minimum space and be free from external projecting parts. A still further object of the present invention is to provide an improved motor whose parts may be very easily assembled or disassembled. These and other objects and advantages of my invention will, however, hereinafter more fully appear.

In the accompanying drawings I have shown one embodiment which my invention may assume in practice, although it is to be understood that the same is used for illustrative purposes only and that the invention is not limited to the embodiment shown therein.

In these drawings,—

Fig. 1 is a longitudinal sectional view of my improved motor.

Fig. 2 is a longitudinal sectional view of the piston used therein, taken on line 2—2 of Fig. 1.

Fig. 3 is a side elevation of one of the cylinder heads.

Fig. 4 is a side elevation, partly in section, of one of the cylinder linings.

Fig. 5 is a view taken on line 5—5 of Fig. 4.

Fig. 6 is a side elevation of a plug.

Fig. 7 is a plan view of another cylinder head.

Fig. 8 is a side elevation of the same head.

Fig. 9 is a section through a modified form of piston, the section being taken on a line corresponding to line 9—9 in Fig. 2.

Figs. 10 and 11 are central longitudinal sections respectively showing the piston near the forward and near the rearward ends of its strokes.

In this illustrative construction I have shown, for purposes of illustration, my improved motor adapted for use in a ground hog drill, in which a casing 1 of the pneumatic motor is a continuation of the drill rod of the ground hog drill, and is preferably attached to the drill rod (not shown) by a coupling 2. As is common in this type of motor, I provide the lower end of the casing 1 with internal threads or other means

for retaining a tool chuck (not shown). Shoulders 4 and 5 formed on the inner ends of the coupling 2 and chuck retainer 3, respectively, define the outer limits of the pneumatic cylinders and provide stopping means against which the cylinder parts may rest during the operation of the tool.

In my preferred form, I preferably insert within the casing 1 a series of cylinder linings 6, 7, and 8, separated by intermediate cylinder heads 9 and 10, so that when the parts are assembled, as shown in Fig. 1, the motor consists of three separate and distinct cylinders. The lower or forward cylinder 8 is provided with a cylinder head 11, and the rear cylinder 6 is provided with a cylinder head or retaining disk 12. In the form of my invention as shown herein, the disk 12 is preferably only a retaining disk for retaining the parts in assembled position (Fig. 1), this disk being held against the cylinder 6 by a spring 13 which abuts against the disk and a shoulder 14 formed in the coupling 2 around a central opening 15 in the coupling. The parts above described may easily be assembled when the casing 1 is free from the coupling 2 by merely dropping the elements of the cylinders in their proper order into the casing 1 and applying the coupling spring and disk, as shown, 80 dowel pins, as shown at 16, being preferably used to retain the lower members in predetermined relative positions.

Any form of cylinder may be used, but in my preferred form I preferably make the cylinder 6 of a different construction from the cylinders 7 and 8, the cylinder 6 being provided, at a point adjacent the rear end thereof, with a shallow recess 17 to prevent the wearing of a shoulder on the cylinder lining 6 during the operation of the motor. Near the forward end of this cylinder 6 I provide a deeper and longer recess or bypass 18 which is preferably spaced slightly from the adjacent cylinder head 9 to provide 100 a cushioning space 19.

The upper cylinder head proper, 9, which separates the cylinders 6 and 7, is preferably provided with a central recess 20 which connects with an exhaust port 21, the latter 105 leading into a longitudinally extending groove 22 cut in the outer face of the cylinder head 9, as is clearly shown in Figs. 1 and 3.

The intermediate cylinder lining 7 and the 110

lower cylinder lining 8 are preferably made identical, though this is not essential to the operation of the motor. Each of these cylinder linings carries adjacent its upper end 5 a plurality, herein six, of short, relatively shallow, longitudinally extending recesses or bypasses 23, the space 24 between these recesses and the lower face of the cylinder head 9 forming an air cushion for one of the 10 plurality of pistons. Near the lower or forward end of each of these cylinder linings 7 and 8, is another series of recesses or bypasses 25, preferably formed in longitudinal alignment with the recesses 23, and preferably slightly longer, these recesses, as shown, being spaced from the adjacent cylinder heads 10 and 11, respectively, a greater distance than the upper recesses are spaced 15 from the cylinder heads 9 and 10 to form larger cushioning spaces 26. The exhaust passages preferably consist of a plurality of passageways equal in number to the recesses 23 or 25, cut in staggered or alternate relation to these recesses, and preferably on the 20 outside of the cylinder linings 7 and 8. By this means, the same tube or lining is made to contain the bypasses 23 and 25 and the exhaust passages 27, in such a manner that a minimum quantity of material is used in 25 the liner and the liner is made to occupy a minimum of space, there being no external projections. As is obvious, the exhaust passages may be formed in the inner wall of the casing or partially in this wall and partially 30 in the outer wall of the lining.

The cylinder head 10 which separates the lining 7 and 8, is almost identical with the cylinder head 9, having a central annular recess 28 formed therein and a port 29 connecting this recess with a longitudinally extending exhaust passage 30, the exhaust passage 30, however, extending the depth of the cylinder head 10 instead of only partially 35 the depth, as in the case of the cylinder head 40 9. These exhaust ports 29 and 21 in the cylinder heads 10 and 9, respectively, are preferably of the same number, herein six, as the exhaust passages 27, and the exhaust 45 passages 30 and 32 in these heads, respectively, are preferably also of the same number as the exhaust passages in the outer face 50 of the cylinder lining and made therewith so that the exhaust may flow from the cylinders' ends through the recesses 28 and 20 55 through a plurality of ports to a plurality of exhaust passages, thereby making it possible to use shallower and smaller exhaust passages, and hence a much thinner and more compact cylinder construction.

The lower cylinder head 11 which abuts 60 against the retaining shoulder 5 formed on the chuck coupling 3, preferably has no central annular recess, as have the cylinder heads 9 and 11, the exhaust from the forward end of the lower cylinder preferably

passing to the tool through a central opening 31 formed in the cylinder head when the striking point is clear of this opening. A plurality of longitudinal grooves 32 extend partly through the outer surface of this cylinder head, mate with the plurality of exhaust passages 27, and connect with diagonal exhaust passages 33 so that the exhaust from the upper two cylinders and the rear end of the lower cylinder is conducted directly to the steel. 75

Within the cylinders I employ a single piston 34 comprising a series of interconnected spaced piston heads 35, 36, and 37. In my preferred form shown, a central, axially disposed fluid pressure passage 38 is formed longitudinally in the piston 34 to conduct pressure fluid to the ends of the different cylinders, this axial passage 38 preferably terminating in a restricted passage 39 80 extending from near the center of the front piston rod 37 through the striking end of the piston to conduct live pressure fluid to the drill steel. 85

The upper piston 35 preferably has two pressure surfaces 40 and 41, the upper surface 40 being, in my preferred form, always subjected to fluid pressure, the lower surface 41 being only subjected to fluid pressure during the cushioning action in the recess 19 or on the up stroke. In this piston head, a plurality of passageways or ports 42 connect the fluid passage 38 with an annular recess 43, although, if desired, these passageways 42 may conduct the fluid to separate and distinct grooves similar to the grooves 23 and 25, formed in the outer surface of the piston head 35 in place of the recess 43 (see Fig. 9). 100

The piston heads 36 and 37 are of identical construction except for the small fluid passageway 39, these piston rods having upper and lower pressure areas 45 and 46, respectively, and radial ports 47 terminating preferably in annular recesses 48. 105

These piston heads 35, 36, and 37 are preferably held in spaced relation by piston rods 49 and 50, preferably formed, as shown herein, integral with the different heads 35, 36, and 37. Each of these sections 49 and 50 is provided at a point near the forward end thereof with relatively shallow annular recesses 51, 52, which govern the flow of exhaust fluid from the different cylinders. 110

If it is not desirable to permit live pressure fluid to pass from the central passageway 38 in the piston 34 to the tool 54, a plug, such as is shown at 53 (Figs. 2 and 6) may be dropped into the piston in the position shown in Fig. 2. The upper surface of this plug 53 is preferably made relatively large so that the fluid pressure used for operating the tool will hold this plug securely in place during the cutting operation. If it is necessary, however, to supply an extra quantity of pressure fluid to the tool to blow the cut- 115 120 125 130

tings away from the cutting end thereof, this plug 53 may be removed by merely disconnecting the coupling 2 from the upper section of the drill rod and reversing the cylinders, when the plug 53 will fall out. As it has been found costly to bore a small hole 39 of the length desired, this hole may be made larger than necessary and the plug 53 may be bored as shown at 53'. If desired, 10 a series of plugs having holes of different sizes may be used interchangeably.

From the foregoing, it is thought that the operation of my pneumatic hammer will be apparent, it being clear that during the 15 downward or forward stroke of the piston live air is supplied through the aperture 15 to the upper surface 40 of the upper piston head 35 and to the upper surfaces 45 of the piston heads 36 and 37 from the passageway 20 38 through the ports 47, recesses 48, and bypasses 23. On the downward stroke, live fluid pressure acts on the upper surface of all the piston heads, thereby transmitting to the tool 54 the added working powers of 25 the different cylinders. On the rearward stroke, the pressure on the upper surface 40 is not relieved, but the pressure on the upper surfaces 45 of the pistons 36 and 37 is relieved by the exhausting of the pressure 30 fluid from the upper part of the cylinder linings 7 and 8 by way of the recesses 51, 52, recesses 20 and 28, ports 21 and 29, to the longitudinally extending exhaust passages formed in the outer surfaces of the cylinder 35 linings and piston heads. The pressure fluid acting on the lower surfaces 46 of the pistons 36 and 37 to return the piston 34 to its upper position, is admitted to the lower end of the cylinder linings 7 and 8 by means of 40 the ports 47, recesses 48, and relatively long recesses 25. As the forward stroke of the piston is accompanied with a greater accumulative pressure on the different piston heads than the rearward stroke, the air 45 cushions 19 and 26 formed in the forward ends of the different cylinder linings are made deeper than the rear cushioning spaces 24 in the upper or rearward ends of the liners 7 and 8. The recesses 25 are prefer- 50 ably made longer than the recesses 23 so as to permit the live air to act for a longer period of time on the lower surfaces 46 of the piston heads 36 and 37 so as to give a quick return to the piston 34, for, as is evident, if the bypasses 25 are of the same length and depth as the bypasses 23, the downward movement of the piston under a pressure of the live fluid acting on the 55 surfaces 40 and 45 of the three piston heads will be much more rapid than the upward movement of the piston 34 under the action of the live pressure acting against the surfaces 46 of the pistons 36 and 37 against the 60 live pressure acting on the large surface of the piston head 40. It will of course be

noted that the surface 41 of piston head 35 is likewise subject to live pressure through passage 42, groove 43, and bypass 18, during a portion of the return stroke and that the force due to this pressure likewise contributes to the overcoming of the pressure 70 acting on the surface 40.

The pressure fluid is exhausted from the lower side of the pistons 35 and 36 by means of the recesses 51 and 52 which, in a pre-determined position of the piston rod 34 in the casing 1, connect the lower end of the liners 6 and 7, respectively, with the exhaust recesses 20 and 28 in the cylinder heads 9 and 10, respectively. It will be noted that 75 because the recesses 51 and 52 are placed nearer the heads 36 and 37, respectively, than the heads 35 and 36, respectively, the exhaust period for the lower ends of the cylinder linings 6 and 7 is much shorter than the exhaust period for the upper ends of the cylinder liners 7 and 8, and that therefore a greater quantity of air is left in the forward end of these cylinders to produce a 80 greater cushioning action. As stated above, the forward end of the front cylinder liner 8 is exhausted directly into the chuck housing 3 when the striking end of the piston has been sufficiently retracted to clear the 85 opening 31.

It should be noted that by the new and improved construction shown herein the entire pneumatic motor may be mounted in the drilling tool of a ground hog drill without changing the size of the casing thereof, it 90 only being necessary to provide a proper coupling 2 and a proper chuck housing 3, although the latter is not necessary where a chuck is not needed to retain the tool. It will further be noted that because of the 95 particular construction used the outer casing 1 may be made of any suitable tubing, it only being necessary to provide liners of special hardened steel to take the wear incident to the operation of the motor. As is apparent, the parts are very easily disassembled by the breaking of one connection, that is, the threaded connection between the casing 1 and the coupling 2, and by reversing or 100 turning the pneumatic motor upside down, when the parts will slide out; and that the parts may be assembled by inserting them in order, as shown in Fig. 1, into the casing 1, the cylinder heads 9 and 10 being preferably split into two or more parts to facilitate 105 the placing of these heads around the respective piston rod sections 49 and 50. It should also be noted that the motor shown herein 110 is of the valveless type, that there are no projecting parts, and, it should further be noted, that by the use of duplicate piston heads 36 and 37 and duplicate cylinder liners 7 and 8, the power of the motor may easily 115 be increased by merely adding more of these 120 duplicate parts, thereby getting a heavier 125 duplicate parts, thereby getting a heavier 130

piston and added pressure areas. These and other advantages of my improved construction will, however, be clearly apparent to those skilled in the art.

5 While I have in this application specifically described one embodiment which my invention may assume in practice, it is to be understood that the same is used for illustrative purposes merely and that the invention may be modified and embodied in various other forms without departing from its spirit or the scope of the appended claims.

What I claim as new and desire to secure by Letters Patent is:

15 1. In a multiple cylinder motor, a cylinder construction comprising a casing member, a plurality of liner members therein, a plurality of heads separating the interior of said cylinder into a plurality of separate piston chambers, said heads comprising a plurality of sectors cooperating to form a unit, and a piston having alternately reduced and enlarged integral portions, said enlarged portions forming piston heads disposed in said chambers while said sectors surround said reduced portions.

20 2. In a motor, a cylinder comprising a casing, a cylinder liner for said casing, live fluid distribution passageways for the motor in the interior of said liner and exhaust fluid distribution passageways for the motor between the liner and the casing, a piston head within said liner having a portion of reduced diameter secured to said head, means carried by said piston head for controlling only the fluid flow to one of said sets of passageways, and means carried by said reduced portion for controlling only the fluid flow to the other of said sets of passageways.

25 3. In a motor, a cylinder, live fluid and exhaust distribution passages for the motor formed therein, a piston in said cylinder comprising a piston head and a reduced portion projecting therefrom, a passage of reduced area located adjacent one end of said cylinder through which said reduced portion passes, means carried by said piston head for controlling only the flow of fluid to said live fluid distribution passages, and means carried by said reduced portion for controlling only the exhaust of fluid to said exhaust passages.

30 4. In a valveless motor, a cylinder comprising a plurality of pressure chambers of equal diameters, a piston having a plurality of heads arranged in said chambers, one of said heads presenting its entire cross sectional area to fluid pressure, means for subjecting said area to continuous live pressure, and means controlled by said piston to supply fluid pressure to other surfaces of said piston heads to overcome the pressure on said circular area.

35 5. In a valveless motor, a cylinder comprising a plurality of pressure chambers of

equal diameters, a piston member having a head reciprocable in each of said chambers, means for subjecting one of said heads continuously to live pressure over an area substantially equal to the transverse area of one 70 of said chambers, and means controlled by said piston for admitting live fluid periodically to a plurality of said heads to overcome said pressure acting on the area first mentioned.

6. In a percussive tool, a cylinder comprising a plurality of pressure chambers, a piston having two surfaces for driving it in one direction and two surfaces for driving it in the opposite direction, means for admitting fluid to the cylinder to exert a constant pressure on one of the first named surfaces during all movements of said piston passages controlled by the piston for admitting and exhausting pressure in one of said chambers to exert an intermittent pressure on the second of said first mentioned surfaces, and means for exerting intermittent pressures on the second mentioned pair of surfaces comprising passages controlled by the piston 80 and ports formed in the walls of said cylinder. 85

7. In a percussive motor, a cylinder, a hammer piston reciprocable therein having a hollow portion at one end, means for constantly supplying live pressure to the end of said cylinder adjacent said hollow end and into said hollow portion, and means for distributing live pressure through the hollow portion in said piston to effect movement in 95 both directions of reciprocation of said piston. 100

8. In a percussive motor, a cylinder having a plurality of aligned fluid pressure chambers formed therein, a hollow hammer piston having a chamber formed therein and having a plurality of heads located in said chambers, means for constantly supplying live fluid pressure from one end of said piston during all movements of the latter 105 and to the chamber therein, and means for supplying fluid pressure through the chamber in said piston and to said cylinder to overcome or to be accumulative with the continuous pressure on said first mentioned end 110 of the piston. 115

9. In a motor, a cylinder having a plurality of fluid pressure chambers formed therein, a piston having a plurality of heads reciprocable in said chambers, said piston having an end provided with a recess, means for continuously supplying pressure to said end and to said recess, and cooperating passages formed in said cylinder and in said piston and controlled by the latter for the supply of fluid from said recess to said chambers and some of said cooperating passages permitting its exhaust therefrom. 120

10. In a valveless motor, a cylinder construction comprising a casing, a plurality of 125

- detachable cylinder linings therein, a plurality of detachable cylinder heads, a piston element in said cylinders, a plurality of said linings being similar and adapted to support a head between adjacent linings, said adjacent linings and head supported therebetween having continuously cooperating passages allowing automatic reciprocation of said piston, and means for holding said linings and heads in said casing. 70
11. In a motor, a plurality of longitudinally arranged cylinders, a plurality of piston heads reciprocable therein, and means for continuously admitting fluid pressure to one face of one piston head during all movements of the latter and intermittently to the remaining faces of said piston heads to continuously reciprocate said pistons. 75
12. In a motor, a plurality of cylinders, a plurality of piston heads of uniform diameter reciprocable therein, and means for admitting fluid pressure constantly to part of the faces of said piston heads during all movements of the latter and intermittently to the remaining faces to continuously reciprocate said pistons. 80
13. In a valveless percussive motor, a plurality of cylinders, heads therefor adapted to be disposed therebetween, a plurality of double acting pistons in said cylinders, cooperating means carried by said pistons and the cylinder walls for controlling the flow of live pressure fluid, and means carried by said pistons and cooperating with a cylinder head between adjacent cylinders adapted to control exhaust pressure fluid alternately from said adjacent cylinders. 85
14. In a motor, a cylinder comprising a plurality of fluid pressure chambers, a piston having a plurality of heads reciprocable in said chambers and a plurality of intermediate portions of reduced diameter, means formed in the walls of said cylinder and in said piston heads for the distribution of live fluid to said chambers, and means formed in said intermediate portions of said piston for the control of the exhaust from said chambers. 90
15. In a motor, a cylinder comprising a plurality of fluid pressure chambers separated by annular head members, a piston having a plurality of heads reciprocable in said chambers and between said head members, intermediate portions passing through said annular head members, means formed in said piston heads and in the walls of said chambers for the distribution of fluid to the latter, and means formed in said intermediate portions and in said head members for the exhaust of fluid from said chambers. 100
16. In a motor, a cylinder comprising a plurality of fluid pressure chambers, a piston having a plurality of heads reciprocable in said chambers, a recess in said piston, and means for supplying fluid pressure thereto, 105
- means for exhausting fluid from said chambers, and means formed in the walls of said chambers and in said piston heads for the distribution of fluid from said recess to said chambers. 110
17. In a motor, a cylinder comprising a plurality of fluid pressure chambers, a piston having a plurality of heads reciprocable in said chambers, a recess extending longitudinally of said piston, means for supplying fluid pressure to said recess, means for exhausting fluid pressure from said chambers, means formed in the walls of said chambers and in said piston heads for the distribution of fluid from said recess to said chambers, and means for discharging fluid from said recess to the exhaust means for said chambers. 115
18. In a percussive motor, a cylinder comprising a pair of aligned fluid pressure chambers, a common cylinder head separating the same, a hammer piston having a pair of heads reciprocable in said chambers and connected by a reduced portion extending through said common cylinder head, means for supplying live fluid to said cylinders to act on the adjacent faces of two adjacent piston heads to actuate the piston, and means formed in said cylinder head and in said reduced portion cooperating to effect alternate exhaust from the adjacent ends of said chambers to substantially atmospheric pressure. 120
19. In a percussive motor, a cylinder comprising a plurality of aligned fluid pressure chambers, a hammer piston having a plurality of heads freely reciprocable in said chambers and connected by reduced portions, motive fluid supply means comprising means carried by certain of said heads for admitting live fluid pressure alternately to each end of their respective cylinders to actuate said piston in opposite directions, and means formed on said reduced portions for alternately exhausting adjacent ends of adjacent cylinders. 125
20. A motor comprising a plurality of cylinders, a plurality of pistons freely reciprocable in said cylinders, means for continuously supplying fluid pressure to one end of one of said pistons during all movements thereof, and means for supplying fluid pressure from said end to the remainder of said pistons to overcome said continuous pressure on said first piston. 130
21. A motor comprising a plurality of cylinders, a plurality of pistons of substantially the same diameter freely reciprocable in said cylinders, means for continuously supplying fluid pressure to one end of one of said pistons during all movements thereof, and means for supplying fluid pressure from said end to the remainder of said pistons to overcome said continuous pressure on said first piston in one direction of movement. 135

ment or be accumulative therewith in the other direction of movement.

22. In a drilling mechanism, a motor cylinder, means for supporting a hollow 5 drill steel therein, a reciprocable piston therein having a bore extending throughout its length and of different diameter at different points, motor distribution passages communicating with said bore, and removable 10 means disposed within said bore for controlling the flow of fluid through the same to said steel.

23. In a multiple cylinder percussive motor, a cylinder comprising a casing having 15 a bore, cylinder liners and heads in said bore forming separate chambers, live fluid distribution passages for the motor on the interior of said liners, exhaust fluid passages for the motor between the liners and heads 20 and the casing, piston heads in said chambers having portions of reduced diameter secured to said heads, means carried by said piston heads for controlling the flow of fluid to one of said sets of passages, and means 25 carried by said reduced portions for controlling the flow of fluid to the other of said sets of passages.

24. In a multiple cylinder percussive motor, a cylinder comprising a casing having a 30 bore, cylinder liners and heads in said bore forming separate chambers, live fluid distribution passages for the motor on the interior of said liners, exhaust fluid passages for the motor between the liners and heads and the 35 casing, piston heads in said chambers having portions of reduced diameter secured to said heads, means carried by said piston heads for controlling the live fluid distribution passages, and means carried by said reduced 40 portions for controlling said exhaust fluid distribution passages.

25. In a multiple cylinder percussive motor, a cylinder comprising a casing having a bore, a plurality of cylinder liners in said 45 bore, live fluid distribution passages for the motor formed in the interior of each of said liners, exhaust fluid passages for the motor formed between said liners and said casing, piston heads within said liners having portions 50 of reduced diameter secured to said heads, means carried by said piston heads for controlling the flow of fluid to one of said sets of passages, and means carried by said reduced portions for controlling the flow of fluid to the other of said sets of 55 passages.

26. In a multiple cylinder percussive motor, a cylinder comprising a casing having a bore, a plurality of cylinder liners in said 60 bore, live fluid distribution passages for the motor formed in the interior of each of said liners, exhaust fluid passages for the motor formed between said liners and said casing, piston heads within said liners having portions 65 of reduced diameter secured to said

heads, means carried by said piston heads for controlling said live fluid distribution passages, and means carried by said reduced portions for controlling said exhaust fluid distribution passages.

70

27. In a multiple cylinder percussive valveless motor, a cylinder construction comprising a casing member having imperforate side walls and a bore substantially throughout its length having a reduced portion at 75 one end thereof, a plurality of sleevelike liner members insertable in said bore, a plurality of head members between said liner members separating the interior of the cylinder in a plurality of separate chambers, 80 said head members comprising a plurality of cooperating sectors, and a hammer piston having alternately reduced and enlarged integral portions, said enlarged portions forming piston heads disposed in said chambers 85 while said sectors surround said reduced portions.

85

28. In a motor, a cylinder construction comprising a casing member having a bore substantially throughout its length, a plurality of cylinder liners insertable in said bore, a plurality of head members insertable in said bore, a closure member secured at one end of said bore, and means for resiliently maintaining said liners and head 90 members in operative assembled relation comprising a spring engaging said closure member.

90

29. In a multiple cylinder valveless percussive motor, a cylinder comprising a casing member having a bore, a plurality of cylinder liners in said bore, a plurality of head members between said liners separating the interior of the cylinder into a plurality of separate chambers, a hammer piston having heads disposed in said chambers, and means for distributing live and exhaust fluid in said motor comprising a constant pressure chamber in said piston and passages formed in said piston, liners, and head members.

100

30. In a multiple cylinder valveless percussive motor, a cylinder comprising a casing member having a bore, a plurality of cylinder liners in said bore, a plurality of head members between said liners separating the interior of the cylinder into a plurality of separate chambers, a hammer piston having heads disposed in said chambers, and means for distributing motive fluid in said motor comprising axially extending inlet and exhaust passage means, a constant pressure chamber in said piston and passages formed in said liners and head members.

105

31. In a percussive motor, a cylinder having enlarged and reduced bores, live fluid and exhaust fluid distribution passages for the motor formed in said cylinder, and a hammer piston in said cylinder having a grooved piston head in the enlarged bore and a reduced portion in the reduced bore,

115

120

125

130

the grooved piston head controlling only the live fluid distribution passages while the reduced portion controls only the exhaust fluid distribution passages.

5 32. In a percussive motor, a cylinder, a hammer piston reciprocable therein having spaced heads and a hollow portion throughout a portion of its length, means for constantly supplying live fluid to the end of said

cylinder adjacent the hollow end and into 10 said hollow portion of said piston, and means for distributing live pressure through said hollow portion in said piston alternately to the opposite sides of said piston heads to effect movement in both directions of reciprocation of said piston.

In testimony whereof I affix my signature.
HENRY H. MERCER.
